UNITED STATES PATENT OFFICE.

GEORGE PIRRUNG, SR., AND FELIX PIRRUNG, OF RAVENSWOOD, ILLINOIS.

DESIGN FOR A BROOM-SHIELD.

SPECIFICATION forming part of Design No. 29,332, dated September 13, 1898.

Application filed August 8, 1898. Serial No. 688,115. Term of patent 7 years.

To all whom it may concern:

Be it known that we, GEORGE PIRRUNG, Sr., and FELIX PIRRUNG, citizens of the United States, residing at Ravenswood, in the county 5 of Cook and State of Illinois, have invented and produced a new and useful Design for a Broom-Shield, of which the following is a specification, reference being had to the accompanying drawings, forming part thereof.

10 Figure 1 is a perspective view showing our design, and Fig. 2 is a sectional view taken on line 2 2 of Fig. 1.

As shown in the drawings, the leading or material feature of our design consists of a 15 trunco cone-shaped piece split longitudinally, with an annular concave groove A in its lower portion. Arranged irregularly over the surface of the piece are convex indentations a

and circular portions B and partly-circular portions B', both of which are left plain and 20 smooth. The indentations a produce a "pebbled" appearance on the surface of the piece, while the circular portions and partly-circular portions are smooth and plain, thus making a greater contrast.

Having described our invention, what we claim as new, and desire to secure by Letters Patent, is—

The design for a broom-shield, as herein shown and described.

GEORGE PIRRUNG, SR.
FELIX PIRRUNG.
